FRANÇOIS J. SCHAETZEL, OF STATEN ISLAND, NEW YORK

DESIGN FOR A TEXTILE FABRIC OR THE LIKE

Application filed November 1, 1932. Serial No. 45,684. Term of patent 3½ years.

To all whom it may concern:

Be it known that I, FRANÇOIS J. SCHAETZEL, a citizen of the United States, residing at No. 800 Brighton Avenue, Staten Island, Richmond County, State of New York, have invented a new, original, and ornamental Design for a Textile Fabric or the like, of which the following is a specification, reference being had to the accompanying drawing, forming part thereof.

The figure is a surface view of a piece of textile fabric or the like, showing the de-

sign. The area within the dot and dash lines shows one complete unit of the design. The repeats are arranged in vertical rows, and adjacent vertical rows are one half a complete unit offset so that the angle of the complete unit indicated by letter A corresponds with angle B of one of the repeats in an adjacent vertical row.

I claim:

The ornamental design for a textile fabric or the like, as shown and described.

FRANÇOIS J. SCHAETZEL.
